UNITED STATES PATENT OFFICE.

KAZIMIERZ GOSCIEWSKI, OF JACKSON, MICHIGAN.

FIRE SAFETY DEVICE.

Application filed November 7, 1927. Serial No. 231,532.

This invention relates to a new and novel fire safety device adapted for the purpose of rescuing persons, valuables or the like from a burning building, or from mines, and the 5 like.

The object of the invention is to provide a fire safety device of novel construction and arrangement of parts, and a means of raising and lowering the said elevator up and 10 down the side of a building.

For further comprehension of the invention and of the objects and advantages thereof, reference will be had to the following description and appended claims and to the accompanying drawing.

Fig. 1 is a side elevational view of my improved device, as same would appear when in use.

Fig. 2 is a similar fragmentary view, illustrating in particular the elevator lifting mechanism as embodied in my improved device.

Fig. 3 is a front elevational view thereof.

Fig. 4 is an enlarged front elevational view 25 of the elevator as embodied in my improved device.

Fig. 5 is a sectional view taken on the line 5—5 of Fig. 4.

Fig. 6 is a top plan view thereof.

Fig. 7 is a side elevational detail view of 30 the conveyor as embodied in my improved device.

Fig. 8 is a top plan view of the device of Fig. 7.

Fig. 9 shows the device attached ready for use.

As here embodied my improved device comprises a drum 10, rotatively supported by a standard 11, and provided with a handle 13, 40 or crank. The above mentioned mechanism is mounted in the bracket 14 with vertical sides, which is secured to the roof of a building 15, adjacent to, the wall thereof. The window member 16 is hinged as at 17 and 18 to extensions 14' projecting from the said sides of bracket 14. The bracket 14 extends slightly beyond the front of the building. The flexible member 19 is attached to a lever 16' rigidly attached to the window 16 below the pivots thereof and is extended downwardly therefrom through a tubular member 20,

secured to the outer wall of the said building, leading to the box 21 secured to the said outer wall adjacent to the ground. The box 21 has slidably mounted therein a door 22, 55 held in a closed position by the wire 23. The handle 24 or ring, is secured to the lower free extremity of the flexible member 19 and is normally positioned inside the said box 21.

The flexible member 25 is normally wound 60 around the drum 10 and is attached thereto, being of suitable length to extend from the drum to the ground. The weight 26 is attached to the free extremity of the flexible member 25 and is normally positioned inside 65 the housing 14, resting against the window 16.

The above described construction and the manipulation thereof is as follows: In event of a fire, the wire 23 is broken, the door 22 opened, the handle 24 is then pulled, for 70 drawing downwards on the flexible member 19 and pivoting the member 16 so that the lower portion moves away from the roof of the building, causing the weight 26 to fall to the ground, which when falling makes a 75 noise to arouse the occupants of the building, serving as a fire alarm. It is obvious that the weight 26 will extend the flexible member 25 from the drum 10 to the ground, for the purpose as hereinafter set forth.

The elevator 27 is of box-like construction, of any desirable size or dimension adapted to accommodate a number of persons and valuables, and is divided into side compartments 28 and 29, adapted to accommodate the 85 above mentioned person, and a central compartment 30, adapted to house the mechanism as hereinafter set forth and described. The doors 31 and 32, are slidably mounted in the rear side of the elevator, so as to permit people 90 from the said building to enter the elevator through the windows of the building. Doors 33 and 34 are hinged as at 35 and 36, respectively, to the front side of the elevator, so as to permit the said people to leave the elevator 95 when reaching the ground. A similar door 38 is hinged as at 39, to the front side of the elevator, so as to permit access to the mechanism mounted in the said central compartment thereof. A plurality of rollers 40 are 100 rotatively mounted in the lug elements 42 and 43', of the rear side of the elevator, and

engage the outer wall of the said building so as to permit the elevator 27 to be more easily raised and lowered.

The drum 43 is rotatively mounted on the 5 shaft 44, carried by the supports 45, positioned in the central compartment 30 and is provided with a handle 46, or crank, as a means of rotating the drum 43. The flexible member 47 is attached to the drum 43, and 10 extended upwardly therefrom through an opening provided in the roof, or top member of the elevator. The latter described construction is such as will permit the free extremity of the flexible member 25, when lowered to the ground, as hereinbefore set forth to be secured to the extended extremity of the flexible member 47, so as to permit the elevator to be raised, so as to allow persons to enter the elevator, from the various rooms of 15 the building. Drums 10 and 48 may be individually operated or simultaneously operated for moving the elevator.

A similar drum 48 is secured to the shaft 49, rotatively mounted on the said supports 25 45 and is provided with a handle 50 or crank; as a means of rotating the said drum 48. The flexible member 51 is normally wound on the drum 48 and is of suitable length to extend therefrom through the door 52, hinged 30 as at 53, thru the roof of the elevator, and to the roof of the building, and is secured thereto, as a means of permitting the said elevator to be raised and lowered in lieu of the above described mechanism, which is secured to the roof of the building.

It will be also understood that the free extremity of the flexible member 25, when extended to the ground as above set forth may be secured to the roof of an adjacent building, or to any suitable portion thereof, so as to be approximately horizontally extended. The conveyor 54 comprises a pair of members, having pulleys 55 and 56, rotatively mounted intermediate thereof, adapted to 40 engage the flexible member 25. The eyelets 57 are secured to the conveyor 54 as a means of attaching flexible members 47' thereto, to which is secured the free extremity of the flexible member 47. The latter described 45 construction is such as will permit the elevator 27 to transport people from the building on fire to the said adjacent building.

I have also provided a flexible member 58 engaged through eyelets 59 secured to the 55 roof of the elevator 27, and secured as at 60, to the central portion of the said roof, to which the free extremity of the flexible member 25, may be attached in event it is desired to raise or lower the elevator from the said 60 mechanism attached to the roof of the building.

It is also understood that the flexible member 61 normally extended over the hooks 62 and 63, secured to the front side of the elevator, is adapted to be attached at one ex-

tremity to any desired portion of an adjacent building 15', the other extremity being attached to any desired portion of the burning building 15 approximately horizontally extended, by means of hooks 64 and 65 secured to the said bracket 11 and to the wall of the said adjacent building 15' so as to permit the persons in the said elevator to pull the elevator when extended from the conveyor, as above set forth, to and from the said burning building as may be required.

Having thus described my invention, what I claim as new and desire to protect by Letters Patent of the United States is as follows:

1. In a safety device of the class described, an elevator adapted to accommodate persons, a drum rotatively mounted therein, a flexible member wound on the said drum and extended through an opening formed in the roof of the said elevator, said flexible member being secured to the roof of a building, as a means of raising and lowering the said elevator, a second drum rotatively mounted in the said elevator, a second flexible member attached to the said second drum and extended therefrom, said second flexible member being secured to the free extremity of a flexible member attached to a drum rotatively mounted on the roof of a building, as a means of raising and lowering the said elevator from the roof of the said building or from the said elevator.

2. In a safety device of the class described, a bracket with vertical sides mounted on the top of a building, a window member pivotally supported on the vertical sides, a drum rotatively mounted in said bracket, a flexible member attached to and wound around said drum, a weight removably attached to the free end of said drum and adapted to normally rest upon the bottom of the window member, means connected with said window member and extending downwardly from the top of said building for rotating said window member to permit said weight to descend for extending said flexible member to the ground, an elevator comprising a casing having spaced apart rear doors adapted to register with the windows of said buildings, rollers on said casing for retaining said elevator in spaced relation to the walls of said building, a drum in said elevator, and a flexible member attached to said second mentioned drum adapted to be extended through the roof of said elevator and attached to said first mentioned flexible member when said weight is removed for facilitating raising and lowering of said elevator by simultaneous manipulation of said drums.

3. A safety device of the class described comprising a drum rotatively mounted on the top of a building, an elevator comprising a casing having rollers thereon adapted to engage the wall of said building for retaining

the casing in spaced relation to the said wall, rear doors in said casing adapted to register with spaced apart windows in said building for permitting persons to step from said windows directly into said casing, a drum rotatively mounted in said casing, and a flexible member comprising one section attached to said first mentioned drum and a second sec-

tion attached to said second mentioned drum adapted to be connected for facilitating raising and lowering of said elevator by simultaneous manipulation of said drums. 10

In testimony whereof I have affixed my signature.

KAZIMIERZ GOSCIEWSKI.
